UNITED STATES PATENT OFFICE

2,213,334

STOKER AND FUEL DISTRIBUTOR
THEREFOR

Washington T. Capps, Baltimore, Md., assignor to
The Standard Stoker Company, Incorporated,
a corporation of Delaware

Original application June 29, 1934, Serial No.
733,142. Divided and this application Decem-
ber 22, 1936, Serial No. 117,123

5 Claims. (Cl. 110—105.5)

This invention relates to stokers and the fuel distributing apparatus used in their connection.

It is one object of this invention to provide an improved arrangement consisting of a stoker conduit and a pressure fluid distributor head, in which arrangement the conduit is provided at each side thereof with a bracket extending into the firing opening and upon each of which brackets a pressure fluid distributor head is seated and secured.

Another object of this invention contemplates a novel connecting means between the pressure fluid distributor head and the firing table, said means consisting of a lug depending from the under side of the distributor head, which lug is arranged to be engaged by a bifurcated portion extending rearwardly from the under side of the firing table.

It is a further object of this invention to provide an expandible and contractible discharge mouth for the stoker conduit, comprising a pair of flexible fuel guiding vanes, one at each side of the conduit, which vanes may be bent transversely of the conduit to form a discharge mouth of the desired shape in order that the delivery of fuel to the distributing device may be controlled.

With these and other objects in view, the invention consists of the features of construction, combination and arrangement of parts, herein-
30 after fully described and claimed, reference being had to the accompanying drawings, in which,

Figure 1 is a side view partly in section and partly in elevation of the stoker and the distributor thereof in the region of the firing opening;

35 Figure 2 is a plan view of the distributor;

Figure 3 is a side elevation of the structure shown in Figure 2;

Figure 4 is a plan view of the distributor head with portions broken away;

40 Figure 5 is a side elevation of the distributor head;

Figure 6 is a sectional view of the distributor head taken on the line 6—6 of Figure 4;

Figure 7 is a sectional view of the distributor head taken on the line 7—7 of Figure 11;

Figure 8 is a sectional view of the distributor head taken on the line 8—8 of Figure 4;

Figure 9 is a sectional view of the distributor head taken on the line 9—9 of Figure 11;

50 Figure 10 is a sectional view of the distributor head taken on the line 10—10 of Figure 4;

Figure 11 is a sectional view of the distributor head taken on the line 11—11 of Figure 8;

Figure 12 is a sectional view of the distributor head taken on the line 12—12 of Figure 8;

Figure 13 is a view in section of the distributor head taken on the line 13—13 of Figure 8;

Figure 14 is a top plan view of the firing table; and

Figure 15 is a fragmentary plan view of that portion of the stoker at the firing opening, parts being broken away and shown in section.

Referring now to the drawings, 3 designates a portion of the locomotive backhead comprising an inner sheet 100 and an outer sheet 101, 4 10 the firing opening therein, while A designates the stoker as a whole which comprises an elevator or delivery unit A². The elevator or delivery unit A² comprises a conduit 10 having a screw 11 15 therein.

The body portion of the elevator conduit 10 extends upwardly and forwardly at a suitable angle of inclination and carries at its upper end or discharge end a distributor A⁷ of the construction hereinafter described, whereby the fuel delivered by the conveyor 11 is discharged through the firing opening into the firebox of the locomotive. At its upper end the conduit 10 is provided with a flanged head or enlargement 21 which is attached to a flanged bracket 22 fastened to the 25 backhead 3.

The distributor A⁷, of steam jet type, Fig. 1, is of novel construction and designed to give great feeding efficiency. It comprises a cast metal body or distributor head section 45 and a detachable firing table 46. The distributor head is provided at each side with a laterally projecting attaching flange 47 whereby it is adapted to be rigidly secured by bolts 48 to brackets 48 formed with the elevator conduit 10 at the sides of and 30 within the firing opening, so as to dispose the head 45 wholly within the firing opening in receiving relationship with respect to the delivery end of the elevator conveyor unit, with the table 46 projecting forwardly a proper distance into 35 the firebox. The body of the distributor head is provided with a bottom wall 49, a front wall 50 and a rear wall 51, and these walls carry a sloping top wall 52 forming an upwardly inclined feed plate or table having a rear supporting portion 53 located below its plane and correspondingly inclined to serve as an abutment to the forward end of the elevator unit. The forward end of the elevator conduit directly above the distributor head also has two deflector wings 22a 40 which guide the coal laterally and forwardly onto the distributor plate or table 46. This plate or table consists of a main body or plate portion extending the full width of the firing opening and having a rearwardly extending reduced projec- 45 50 55

tion 56 lying in the plane of its upper face and which extends over and rests upon the ledge or shelf 54 of the distributor body.

The table is also provided with a basal projection 57 which extends outwardly beneath the ledge or shelf 54 and beneath the rear wall 51 of the distributor head 45 and terminates in a bifurcated, slotted or forked portion 58, adapted to receive and engage a lug or projection 59 on the distributor head, the arms of said forked portion 58 being provided with downturned lugs or hooks 58' lying on opposite sides of the lug 59. The table 46 and the ledge or shelf 54 of the distributor body are apertured, as at 46a and 51a respectively, for passage of a fastening bolt 60, while the lug 59 is apertured for the passage of a cotter pin or other suitable fastening 61. By this construction of the table and its mode of attachment to the distributor body or head, the table is detachably mounted in position so that it may be readily applied and removed for renewal or repairs without disturbing the head or detaching it from its position, and connections are provided which are readily disconnectible at any time whenever it is found necessary to detach the table for renewal or repairs or to permit more convenient access to the distributor head for the same purpose. The table is provided with a suitable number, form and arrangement of guide ribs 62 for properly spreading and guiding the fuel in advance of the jet portion of the distributor head.

The fuel feeding over the top of the distributor head drops down over and between a transverse series of vertically disposed projections 63 extending forwardly from the front wall 50 at an elevation above the table upon which the fuel falls. The projections 63 serve as combined rifles and jet nozzles overhanging the table and spaced relatively to each other so that the larger particles of coal will be separated from the dust and finer particles, the larger particles being carried forwardly onto the table, while the dust and smaller particles drop down through the spaces between the projections. In order to facilitate the separation of the finer particles and dust from the lumps and larger particles, the surface 52 is provided with grooves or passages 64 of special form, as hereinafter described. The projections are arranged in equal numbers on opposite sides of the longitudinal center of the head and are arranged at such angles as to properly direct the steam blasts or jets forwardly and at divergent angles in a forward direction to effect a spreading of the fuel uniformly over the surface of the table and into the firebox.

The head is provided with hollow forward side walls 65 forming steam compartments, and the forward walls of these compartments join the guide walls 22a and extend at oblique angles to the body so as to face forwardly and toward the opposite sides of the firebox. These walls extend forwardly beyond the front wall or face 50 and are provided with jet apertures 66 arranged to deliver jets of steam to sweep the coal at the sides or corners of the table into the firebox. The body is also divided by an inclined longitudinal partition 67 into a bottom steam chamber 68 and a top steam chamber 69, which top steam chamber is further divided by an upright partition 70 into compartments located on opposite sides of the longitudinal center of the head. The guide walls 22a are in the form of thin, flexible steel plates, which are firmly secured at their rear ends to the conduit 10. If it is desired to change the direction of the fuel in its passage to the distribu-

tor, the flexible steel plates may be bent or sprung so as to form a variably extensible and contractible discharge mouth for the elevator conduit.

It will be observed that the grooves 64 in the sloping surface 52 of the steam jet head are of minimum depth at their lower ends and gradually increase in depth toward their upper ends where they intersect the spaces between the projections 63. The purpose of these grooves 64 is to carry the dust and fine coal to the projections 63, between which they fall downwardly to the distributing table 46 and between the ribs 62, where the fine dust or coal will be blown by the bottom jets from the plate between the ribs 62 at a light pressure evenly over the fire bed. The jets that blow between the ribs 62 have outlets 74 communicating with chamber 68 only, supplied with steam by a pipe 71 controlled by an individual valve in the cab. The heavier or coarser coal, on the contrary, is carried over the projection 63, where it falls downward on the firing table 46, and a large portion of it rests on the ribs 62 which guide the coal forward under pressure from the steam jets in chambers 69 and 69a, which chambers are divided by the wall 10, the pressure required from these jets being considerably greater than that furnished by the other jets because of the coal being so much heavier and larger than the finer coal particles blown forward by the jets issuing from the bottom chamber 68.

The chambers 69 and 69a are supplied with steam through pipes 71a secured in ports 71b and 71c, which pipes are provided with controlling valves in the cab whereby the supply of steam thereto may be controlled. Each of these pipes 35 is furnished with an individual valve so that the chambers 69 and 69a can be operated at varying pressures independently of each other. The steam in the chambers 65a and 65b supply the steam for the jets 66 which feed the coal forward at the corners of the distributor. These chambers are supplied with steam through the pipes 71d and 71e having controlling valves in the cab so that the supply of steam thereto may be regulated and controlled.

By means of my improved construction of steam jet head and manner of separating the fine coal from the coarser coal it has been found that considerable fuel economy is obtained, in that the finer coal can be distributed evenly over the fire bed and that it will be held down to a considerable extent by the higher jet pressures which feed the heavier coal forward and which are normally operated at a pressure from one-third to one-fourth greater than the pressures of the other jets. The arrangement of the ribs 62 on the firing table 46 has also been found to be highly advantageous, these ribs being curved toward each side of the firebox and so located as to guide the coal so that it will reach all portions of the firebox simultaneously.

While the structure disclosed for purposes of exemplification is preferred, it will, of course, be understood that changes in the form, construction and arrangement of parts within the scope of the appended claims may be made without departing from the spirit or sacrificing any of the advantages of the invention.

This application is a division of my copending application Serial No. 733,142, filed June 29, 1934, for improvements in Locomotive stokers, now Patent No. 2,074,301, granted March 16, 1937.

I claim:

1. In combination, a firebox having a wall with 75

a firing opening therein, a stoker fuel distributor mounted in an operative position at said firing opening and comprising a pressure fluid distributor head and a firing table, said distributor head having a front wall provided with jet apertures directed toward said firebox, a ledge extending forwardly from said front wall below the said apertures, and a lug depending from the under side of said distributor head rearward of said ledge, said firing table being seated upon said ledge and having an upper fuel supporting surface disposed below said apertures, a basal projection formed at the under side of said firing table and extending rearward of the fuel supporting surface thereof, said basal projection tapering laterally and having a bifurcated portion at its reduced rearward end which straddles the lug of said distributor head, and securing means extending through said lug for engaging the bifurcated portion of said basal projection.

2. In combination, a firebox having a wall with a firing opening therein, a stoker feed conduit having its discharge end communicating with said firebox through said opening, the discharge end of said conduit having a bottom wall terminating within the firing opening, said conduit having side walls which are spaced inwardly from the sides of said firing opening and extend thereinto to form with said bottom wall a channel through which fuel is urged toward said firebox, a bracket formed at each side of said bottom wall and being disposed in the space included between the sides of the firing opening and the side walls of said conduit, and a pressure fluid distributor head in said firing opening, said distributor head being provided with a laterally extending flange at each side thereof adapted to seat upon a respective bracket of said conduit, said distributor head extending rearwardly and downwardly between said brackets beneath the bottom wall of said conduit, and securing means extending into the respective brackets and flanges for fastening said distributor head to said conduit.

3. In combination, a firebox having an upright wall provided with spaced inner and outer sheets with a firing opening therethrough, a stoker fuel distributor mounted in operative position at said firing opening, said distributor including a pressure fluid distributor head positioned in said firing opening between the inner and outer sheets of said upright firebox wall and a firing table extending forwardly of said distributor head into said firebox, said distributor head including a plurality of pressure fluid chambers, a front wall having jet apertures therein in communication with said pressure fluid chambers, a hollowed wall at each lateral extremity of said front wall and extending forwardly therebeyond, one side of a hollowed wall together with the respective side of the other hollowed wall including therebetween the jet apertures of said front wall, the opposite side of each hollowed wall being provided with jet apertures directed obliquely away from said front wall, said distributor head being disposed in said firing opening with its front wall between the planes of the inner and outer sheets of said firebox upright wall and said hollowed walls extending forwardly to approximate-
ly the plane of the inner sheet of said firebox wall, the jet apertures in the front wall and

hollowed walls of said distributor head being directed across the upper surface of said firing table.

4. In combination, a firebox having a wall with a firing opening therein, a fuel feed conduit having its discharge end communicating with said firebox through said opening, the discharge end of said conduit having a bottom wall sloping upwardly and forwardly and terminating within the firing opening, a ledge formed at each side of said bottom wall and sloping downwardly and forwardly from the forward edge of said bottom wall, a pressure fluid distributor head in said firing opening, said distributor head having a laterally extending flange at each side thereof seated upon a respective ledge, means extending into said ledges and flanges for securing said distributor head to said fuel feed conduit, said distributor head having a fuel supporting top wall sloping upwardly and forwardly to form a continuation of the conduit bottom wall, a portion of said distributor head projecting rearwardly between said ledges, a ledge formed with and extending forwardly from the lower forward side of said distributor head, a firing table seated on said last named ledge, a projection formed with said firing table and extending rearwardly beneath said last named ledge, means associated with the under side of said distributor head and the rearwardly projecting portion of said firing table for securing said table to said head, said distributor head having a front wall provided with jet apertures above the level of said firing table and directed thereacross.

5. In combination, a firebox having a wall with a firing opening therein, a fuel feed conduit having its discharge end communicating with said firebox through said opening, the discharge end of said conduit having a bottom wall sloping upwardly and forwardly and terminating within the firing opening, a ledge formed at each side of said bottom wall and sloping downwardly and forwardly from the forward edge of said bottom wall, a pressure fluid distributor head in said firing opening, said distributor head having a laterally extending flange at each side thereof seated upon a respective ledge, means passing through said ledges and flanges for securing said distributor head to said fuel feed conduit, said distributor head having a fuel supporting top wall sloping upwardly and forwardly to form a continuation of the conduit bottom wall, a portion of said distributor head projecting rearwardly between said ledges, said rearwardly projecting portion having a depending lug, a ledge formed with and extending forwardly from the lower forward side of said distributor head, a firing table seated on said last named ledge, a basal projection formed at the under side of said firing table and extending beneath and rearward of said last named ledge, said basal projection having a bifurcated rearward portion receiving said depending lug, means extending into said lug and bifurcated portion for securing said firing table to said distributor head, said distributor head having a front wall provided with jet apertures above the level of said firing table and directed thereacross.

WASHINGTON T. CAPPS. 70
